UNITED STATES PATENT OFFICE.

LOUIS A. ALTIERI, OF SAN FRANCISCO, CALIFORNIA.

DIRECTION-INDICATOR FOR AUTOMOBILES.

1,320,822.

Specification of Letters Patent.

Patented Nov. 4, 1919.

Application filed April 16, 1919. Serial No. 290,409.

To all whom it may concern:

Be it known that I, LOUIS A. ALTIERI, a citizen of the United States, residing at the city and county of San Francisco and State of California, have invented new and useful Improvements in Direction-Indicators for Automobiles, of which the following is a specification.

This invention relates to a direction indicator for automobiles.

It is the principal object of this invention to provide a direction indicator adapted to be used upon vehicles and by which the intended course of travel of the vehicle may be indicated, and which device is simple in its operation, will automatically operate to illuminate an indicating semaphore when a signaling position is desired and is so designed as to be useful either in the daytime or at night to perform its indicating function.

The present invention contemplates the use of a central cylindrical lamp house, around the body portion of which two semaphores are adapted to swing in opposite directions, said semaphores being actuated by control means which will permit them to be separately or simultaneously moved to a signaling position and to be automatically illuminated when reaching this position.

The invention is illustrated by way of example in the accompanying drawings, in which—

Figure 1 is a view in elevation, showing the indicator as signaling for a right-hand turn and further indicating by dotted lines the position of the left-hand signal.

Fig. 2 is a view in vertical section on the line 2—2 of Fig. 1, showing the details of construction of the lamp house and the semaphores.

Fig. 3 is a view in horizontal section on the line 3—3 of Fig. 1, showing the manner in which the lamp house and semaphores coöperate to permit the illumination of the semaphores "green".

Fig. 4 is a view in perspective illustrating the arrangement of the lamp house.

Fig. 5 is an enlarged view in vertical section, showing the operating mechanism of one of the push-buttons by which a semaphore is controlled.

Referring more particularly to the drawings, 10 indicates a cylindrical lamp house, here shown as being of a single diameter throughout its interior and being formed

exteriorly with reduced end portions 11 and 12. These end portions are separated by an intermediate enlarged flange 13. The reduced end portions are adapted to receive 60 the circular hub of indicating semaphores 14 and 15. These semaphores are preferably formed of sheet metal and are hollow, as clearly indicated in Figs. 2 and 3. The front of each semaphore is open and is closed by 65 means of a transparent screen 16, upon which suitable indicia is inscribed.

In the present instance this indicia is "Stop" and is printed in the manner to be readily read either in the daytime or at night 70 when illuminated. The head portions 17 and 18 of the semaphores 14 and 15, respectively, are formed with slotted openings 19 at one side in their circumference. These openings are adapted to register separately 75 with openings 20 and 21 formed through the reduced portions of the lamp house; the registering operation taking place only when the semaphore arm is standing in its horizontal signaling position. Due to this 80 arrangement the semaphore arms may be illuminated, when signaling, by means of a lamp 22 secured to an end member 23 which is fixed in the end of the lamp house. The end member 23 is secured to a bracket 24 by 85 which it may be conveniently mounted upon the vehicle.

Operation of the semaphore arms is intended to be produced from the dashboard of the vehicle and for that reason each arm 90 of the semaphore is fitted with a lug 27, by which the semaphore may be rotated around the body portion of the lamp house and which will dispose the semaphore arms in their illuminated position; it being understood that the arms are only illuminated 95 when standing horizontally. While a name plate 25 is intended to be continuously illuminated by means of the lamp 22 as it shines through a slotted opening 26 formed through 100 the collar 13 of the lamp house, further illumination of the direction indicator is afforded by means of a colored glass 9 which is secured in the outer opened end of the lamp house, and which will serve as a tail 105 light at all times.

The ears 27 are each secured to operating cables, here shown as cables 28 and 29. These cables are preferably led through a flexible conduit 30, which is led to the dashboard 31 110 of the vehicle and from which point the semaphore arms are operated.

As shown in Fig. 5, the dash-board of the vehicle is fitted with the mountings 32, through which the ends of the cables 28 and 29 are led. It is preferable that two sleeves 5 be provided, each of which is fitted with a 10 slideable plunger 33. One of the plungers 15 operates one semaphore arm and the other plunger is provided to actuate the other arm. An annular groove 34 is formed around the 20 end of each plunger and is adapted to be engaged by a yieldable spring 35, which will normally hold the plungers 33 in their outermost positions. This will also support the plungers so that the semaphores will both 25 be held in vertical positions and will be easily influenced by the action of the cables upon the lugs of each semaphore arm.

In the operation of the present invention, it is assumed that both the plungers 33 are 30 in the position indicated by full lines in Fig. 5. If it is intended to turn to the right, the driver pulls outwardly on the right-hand plunger, and this will draw the cable 28 to 35 allow the semaphore arm 14 to move to its horizontal position shown in Fig. 1.

As the semaphore arm moves to its horizontal position the opening 19 in its hub will register with the opening 21 in the lamp-house, and this will cause the rays of 30 the lamp to pass out through the tubular semaphore arm and illuminate the screens 16. When the course of the vehicle is again straight ahead the semaphore arm 14 is raised to its original non-signaling position 35 by pushing upon the plunger arm 33 and swinging this right-hand plunger from the dotted line position shown in Fig. 5 to its original long position. In the event that full stop is desired, the plungers 33 may both 40 be forced inwardly and will cause both of the arms 14 and 15 to fall horizontally in line and in position to become illuminated.

When the present invention is used in the day time, there is no need for illumination, 45 as either of the signs may be readily observed and movement understood to indicate the intended direction of travel of the vehicle.

It will thus be seen that the device here 50 disclosed is entirely devoid of complicated

operating mechanism, and that, in its present form will be easy to manufacture, simple as to manufacturing costs, and, when installed, will operate without objectional breakage or the requirements for repairs and renewals, as is the case with many indicators of this type.

While I have shown the preferred form of my invention, as now known to me, it will be understood that various changes in 60 the combination, construction and arrangement of parts may be made by those skilled in the art without departing from the spirit of the invention as claimed.

Having thus described my invention, what 65 I claim and desire to secure by Letters Patent is:

1. A direction indicator comprising a cylindrical radially slotted lamp-house, a pair of semaphore arms independent sleeves carrying the arms and mounted to rotate around said house, operating means for selectively swinging said semaphore arms from their pivotal mounting upon the lamp-house, and means whereby movement of the semaphore 75 arms from a non-signaling to a signaling position will cause them to be illuminated from the lamp-house.

2. A direction indicator of the character described including a horizontally disposed, cylindrical lamp house, independent sleeves mounted and turnable about the lamp house, hollow arms radiating from said sleeves having transparent visible indicia, a lamp in the lamp house in line with the arms, open 80 slots made in the sides of the lamp house with which the arms register when turned to an indicating position, a fixed number plate exposed to the light through a slot in the lamp house, and means to turn either of 85 the sleeves and arms to an indicating position.

In testimony whereof I have hereunto set my hand in the presence of two subscribing witnesses.

LOUIS A. ALTIERI.
